REPLACEABLE VALVE ASSEMBLY

Aurelio T. Riva, Habana, Cuba

Application November 21, 1938, Serial No. 241,693

1 Claim. (Cl. 251—156)

My invention relates to improvements in valve constructions and more particularly to replaceable valve assemblies.

One of the principal objects of my invention is to provide a replaceable valve seat together with correlated and associated parts whereby a faucet having a worn or distorted valve seat may have assembled therein said replaceable valve seat and parts and thereby avoid the necessity of discarding the faucet.

Another object of my invention is to provide a device of the character described which is simple in construction, durable in use, efficient in operation, adapted for use in faucets of ordinary construction, and economical in manufacture.

Other objects and advantages will be apparent from the following description, appended claim and annexed drawing.

Referring to the drawing wherein like reference characters designate like parts throughout the several views:

Figure 1 is a longitudinal sectional view of a faucet of ordinary construction having my invention associated therewith.

Figure 2 is a vertical sectional view of the valve housing of my novel form of valve seat assembly.

Figure 3 is a fragmentary side elevation of the lower section of the valve stem.

Figure 4 is a detail perspective view of my novel form of valve seat.

Figure 5 is a detail perspective view of my novel form of valve member.

Figure 6 is a detail sectional view taken on the line 6—6 of Figure 1.

In practicing my invention, I provide a valve assembly 5 comprising a housing 6 fashioned with an upper externally threaded cylindrical section 7 and a lower skirt section 8. The upper section 7 is threaded into a valve casing 9 of a faucet 10 of ordinary construction, the latter being equipped with an intake passage 11 and a discharge passage 12 separated from said intake passage by means of the usual wall 13 having a communicating opening 14 formed therethrough.

Ordinarily, a valve member is operable within the valve casing for direct engagement with the wall 13 to close the opening 14 whereby to preclude a flow of liquid through said faucet. However, in lieu of a valve member of ordinary construction having seating engagement directly with the wall 13, I provide a disk-shaped seat member 15 positioned on said wall 13 and formed with an aperture 16 in registry with the opening 14. The lower end of the skirt section 8

engages the member 15 and maintains the same

fixed on the wall 13 and said skirt section is open at the bottom and has one side thereof in communication with the passage 12 whereby to permit a flow of liquid through the faucet. A pair of oppositely disposed slots 17 are fashioned in the skirt section and accommodate therein ears 18 formed on a disk-shaped valve member 19 and said valve member 19 is provided with a vertically extending threaded shaft 20 threaded into a socket 21 fashioned in the lower shouldered end of a valve stem 22 rotatably mounted in the upper section 7 of the housing.

The under face of the valve member 19 has secured thereto, by means of a screw 23, a replaceable washer 24. The upper section of the valve stem 22 extends through a packing gland 25 formed within the inner section of a cap 26 threaded on the upper end of the valve casing 9 as clearly illustrated in Figure 1 of the drawing. The upper end of the valve stem has secured thereto a hand wheel 27 for rotating the stem.

Upon rotation of the stem, in one direction, the valve member 19 is actuated downwardly whereby the washer 24 seats on the member 15 and closes the aperture 16. Operation of the wheel in an opposite direction effects a reverse operation of the valve member and thereby opens the aperture 16. The valve member 19 is raised and lowered due to the threaded connection with the valve stem and coaction of the ears 18 with the slots 17.

From the foregoing it will be apparent that I have provided a simple and efficient valve assembly that can be readily applied to faucets of ordinary construction having worn or distorted valve seats and thereby utilize the faucet housing and effect a resultant economy.

It is obvious that the invention is not confined to the herein described use therefor as it may be utilized for any purpose to which it is adaptable. It is therefore to be understood that the invention is not limited to the specific construction as illustrated and described, as the same is only illustrative of the principles of operation which are capable of extended application in advance forms, and that the invention comprehends all construction within the scope of the appended claim.

What I claim is:

In a valve of the type having an inlet and outlet separated by a seat and a chamber outwardly of said seat and having a lateral port and extending therefrom a cylindrical bore, a replaceable valve unit adapted for arrangement in said

bore by threading therein, said unit comprising, a valve housing having integrally formed upper and lower sections, said upper section being exteriorly threaded and adapted for a tight-threaded fit with said bore and adapted to extend between the upper and lower ends of said bore and superjacent said chamber whereby to form a seal with the wall defining said bore to preclude seepage of liquid from said chamber upwardly 5
10 within said bore, said lower section adapted to be positioned solely within said chamber and fashioned with an open bottom and an apertured side for cooperation with said lateral port, said lower section formed with radially extending and 15 oppositely disposed slots adapted to be closed by the wall defining said chamber, said slots adapted to extend throughout the length of said chamber and the length of said lower section and whose upper ends terminate at the jointure of said lower section with said upper section, a replaceable valve seat member adapted to be arranged about and over the seat of said valve and circumjacently maintained thereon by said lower section 20

to provide a valve seat for said valve, a valve member arranged within said lower section for movement therein and formed with ears slidably operable in said slots and coacting with the walls defining said slots to preclude rotation of said valve member relative to said housing and said seat member, said housing fashioned with a lengthwise bore having upper and lower end portions with the upper end portion of a larger diameter than the lower end portion and defining therebetween a shoulder, a valve stem having a lower end rotatably mounted in said lower end portion of said lengthwise bore and fashioned with a collar superjacent said lower end and seated on said shoulder for precluding downward movement of said stem relative to said housing, and means connecting said stem to said valve member whereby upon rotation of said stem axial movement of said valve member is effected with respect to said replaceable valve seat for controlling communication between said inlet and outlet. 5
